(54) **PLANKING VESSELS**

(76) Inventor: **Thomas Blanchard**

Thomas Blanchard of the City and State of
New York -

Letters Patent.

The schedule referred to in these Letters Patent and making part of the same containing a description in the words of the said Thomas Blanchard himself of his improvement in the art of fastening together, the planks or boards of a vessel or boat's bottom, sides, or deck

To all to whom these presents shall come
Be it known, that I, Thomas Blanchard of the County of New York and State of New York, have invented a new and useful Improvement, in the Art of fastening together the planks, or boards, of a vessel or boat's bottom, sides, or deck, and that the following is a full and exact description of the improvement

I lay a keel of proper length and size corresponding to the boat intended to be made, with a stem and stern piece rabited in a proper manner to receive the planking, on the upper side of this keel at suitable distances apart, I place rods or metallic bars which I bend to a proper curve varying the curvature, according to the shape and form of the boat, I intend to爆 the centres of the curve, of these rods and bars, are made fast to the keel with their ends extending upwards, as high or a little higher than the gunwale of the boat, these rods may vary in number & size and distance apart according to the size of the boat required These rods are made fast to the keel of the boat, by a keelson timber, extending over all the rods and made fast to that part of the rods, that rests on the keel by screws or nails holding them firmly upon the keel. The upper ends of these rods, are slightly

attached to a spelling, sprung from stem to stern, forming the curve of the gunwale of the boat and which serves for the purpose of steadyng and keepyngh them in their proper place, while planking the boat, thus forming the skeleton of the boat, similar to the ordinary way of boat-building. The planks are cut to this length, width, and shape, as in the ordinary way of planking except that their edges are cut to such a bevel, or angle as will form a perfect joint and are placed against the outside of said rods, The rods may be partly bedded into them or only rest against them over said rods, and near each edge of the planks may be fixed, a clamp, or bracket, which may be a piece of hoop iron, or other metal, bent curving over the rods with each end fitting to the planks, with sufficient bearing to admitt one or more hole in each end for the purpose of inserting nails or screws, which hold them firmly to the plank, but not so close as to prevent the planks from setting together to form a perfect joint. These brackets, or, clamps must be fixed to all the plank whenever the rods cross them. Thus all the plank may be fastened to the rods except the wale-plank, which are the uppermost, and which form the gunwale of said boat, into which the row-locks are fixed. These planks instead of being fastened by brackets are made at least one third thicker than the other planks and have holes bored through them of a proper size to receive the end of each rod on which is cut a male screw. These rods must pass through the end extending above the gunwale numbers sufficient by far to receive a nut and washer on the end of each, and every rod and by screwing down upon all of them, each and every plank is brought to a perfect joint and the whole boat rendered firm and stiff, a small screw pin should be inserted into the centre of the planks at their joints behind the rods, to prevent their slipping by each other. The end of the whole plank not mentioned that comes in contact with

the stem, and stern timbers must not be firmly fastened to them, till the plank are all brought to their proper joint as above described, after which they may be fastened with screw bolts or otherwise. The Thwarts or cross timbers of the boat are placed at the usual height above the floor for a seat or bench to be placed on them, the ends of these timbers are cut to an angle that will fit the inside of the plank and are butted against them resting on a cleat under them, which is made fast to the plank and extending inside nearly the whole length of the boat, covering all of the rods which are bedded into them and the cleats, firmly fastened to one of the planks on each side running nearly or quite their whole length in the under side of said thwarts or ^{cross} timbers, a groove is cut large enough to admit a small rod, which extends the whole length of the thwarts, and through the sides of the boat above the water line, are brought and held firmly against the butts of the thwarts above described. Thus all the cross timbers are firmly born against the sides of the boat which keeps the boat from spreading, while at the same time it forms a foundation for all the seats. A stanchion is fixed in an upright position, the downward end resting on, or tensioned in the described keelson, the upper ends bearing against the under side of the thwarts, near their centre, which will prevent them from settling down. Diagonal braces may be fixed, when useful, one end of which may rest against the thwarts, near their centre, and extending at their downward ends and coming in contact with the sides of the boat, about half the distance from the floor to the ends of the thwarts and made fast to a short cleat extending only over the two nearest rods at the ends of the braces above described, these diagonal braces will serve to keep the boat from working and prevent it

slipped form, that I have described, the method of applying
said mode of fastening together ordinary simple whale
boats, and planking boats, &c. I will now describe the
manner of forming a deck by this mode of fastening and
attaching it to a boat as above described.

Rods of sufficient length to reach from one
gunwale to ^{the} other are passed through them a sufficient
distance to admit of a screw, nut and washer outside of
the gunwale, these rods are bent to curve or crown
corresponding to the curve or crown of the deck, and
put at convenient distances apart the whole length of
the boat. The deck boards, or planks are cut to the
width, length and shape required for ordinary boats placed
on the upper side of said deck rods, and fastened to them
by brackets in the same manner as the sides of the boat
are fastened as above described and by the same method
brought to a perfect joint that is by the screw, on each
end of the rods, outside being drawn up till every plank
of the deck is brought as close as will render it im-
perious, to water, while at the same time the screws
that pass through the gunwale before described, hold
the deck down and bring the under side of the gunwale
timber to a joint with the sides of the boat, to render
the deck capable of sustaining the necessary weight.
I fix stanchions to the keelson, as above described with
their upper ends rising to a timber which runs horizontally
under the whole length of the deck, on which the deck
rods rest, which prevents the deck from settling down.

To prevent the sides of the boat from spreading by
the pressure upon the deck, rods are fixed under the deck
at suitable distances apart passing through each gunwale
in a straight line from one gunwale to another, these
rods being in a straight line and not crowning like

the rods of the deck on which the deck plates are fastened will when brought to a proper tension by the screws outside of the gunwale, rather serve to raise the deck still more crowning, and prevent the pressure on the deck from spreading the sides of the boat apart, knees may be fixed under the deck at suitable distances, after the sides and deck are brought to their proper bearings; by the method above described, carlings or timbers may be also placed under the deck made fast at each end to the gunwale and sets on cleats bolted or fastened to the sides of the boat for the purpose of sustaining the deck, where great strength is required, boats of great length may be built with their sides rising higher towards midships, than the bow and stern, which serves to stiffen them, and prevent their hogging, these sides above the water line may rise perpendicularly and be decked over, Croptimbers should be placed at suitable distances below the deck to serve as braces, with rods grooved into them passing through the sides of the boat, & with screws outside of the boat will bring the sides of the boat against the ends of the croptimbers to hold the sides firm, and prevent them from spreading.

When two boats are connected together for a steam boat for instance, above the gunwales of each boat, carlings or beams may extend across both boats extending over the outside of each boat, sufficiently far for the guards of the boat, these beams may be fastened to each boat by the rods that form the sides of the boat extending above the gunwales of the boats high enough to pass through said beams, and by screwing them fast to the gunwales of both boats, Both boats may be connected together and a deck formed above them covering both boats, and the space between them on which cabin may be erected, It may be however more convenient to have separate rods, or bolts passing through the deck beams, and through the gunwales of the boats, than to increase the length of the rods or sides of the boat for that purpose, This mode of fastening may be applied to every long boat, and boat made

sharp at both ends, without a keel or stem and sternpost, in the ordinary way, which is done by diminishing the angle or curvature of the body towards the ends of the boat, to a small compass, and also covering the planks narrower towards the ends in the same proportion, by which means, a boat may be brought almost to a point. By this mode of fastening the planks may be made much thinner than in the ordinary mode of fastening, there being no necessity for caulking. The screws that hold on the brackets should not go through for they will interfere with the driving of the outside of the boat, and forming a smooth surface. For making very small boats with thin sides or planking, too thin to fasten the brackets with wood, brass, wrought iron or copper nails, may be substituted with proper clinches, outside of the planking, which may be driven down smooth, and made level with the outside surface of the boat. Fittings such as knees, putlocks and other kinds of frame work may be put into boats or vessels, having this method of fastening, after the fastenings are properly made, and the planking brought to a proper point for the purpose of greater solidity, but which I do not claim as my improvement. Instead of round rods, wide flat bars may be used bent to the curve of the boat edges which will serve to stiffen the boat more than round rods or flat bars bent flatwise, when extreme long bars are necessary they may be put in in several pieces and bolted or riveted together, or the lower ends of them may be made fast in the keel with heads, or screws, which might in some cases be more convenient; or round rods may be passed through the centre of the planks, and supersede the necessity of brackets; instead of cutting a male screw on the end of the rods or bars, the rods may be made with a socket or bent at right angles and a female screw made in them and a bolt with a head on one end, and the other passed through the boarng or

guarantees, having a male screw cut, to enter the female screw just mentioned. This arrangement would prevent the necessity of having the thread of the screw outside of the cap, and exposed to the salt water which would be likely to waste or corrode them. Flat bars may also be put outside of the planking, and bedded into them and screws attached to their ends in the same manner as those inside which would add a greater degree of solidity to the work. The principle of this invention, is to be found in the mode of joining together planks or boards of a ship, or vessel or boat bottom, in the form or curvature intended and also the decks of vessels, and fastening them so as to form the hull or bottom, or deck of vessels or boats with less material and yet of equal strength, in comparison with vessels, or boats, of a clumsy construction. This mode is cutting the edges of the planks, or boards, and fitting them together according to the form intended with, or without dowels, or tongues or grooves so that when the planks or boards are placed in their proper position and the edges thus cut are pressed together by a mechanical power acting with sufficient force, and these planks or boards are by suitable mechanical means, drawn or forced inward at the same time, and kept firmly in the intended form or curvature by such mechanical power, and by suitable cross braces, corresponding with the form, or curvature intended. The edges of said planks or boards will form permanent close joints. The aforesaid mechanical force and means need being so constructed substantially as aforesaid, that the action of said force and means will be simultaneous on the edges to press them together, and on the planks or boards to draw and force them inward. The brackets applied to the inner side of the planks or boards, are iron rods, with screws extending from gunwale to gunwale where no heel or keelson is laid or from the heel or keelson where there is one, and the braces or cross beams placed with

and extending from side to side according to the form or curvature, intended as above described are the mechanical means deemed most expedient by the applicant. Yet there are divers mechanical means which may be used instead of these in part, as for example, keys instead of screws, and also wedges might be used to force and press the edges of the planks or boards inwardly, so that after pressing the edges of the planks or boards together, these may be secured by any common fastening to the frame floor timber fullsides, or ribs of a vessel or boat or the planks or boards may be bored through from edge to edge, so that the rods may pass through them and this may be relied upon instead of the bracket, or rings or staples may be used instead thereof and so chains may be used instead of rods, and elastic wire even substituted for the rods in small constructions.

But the principle of this improvement consists in the simultaneous action, and continued force of mechanical means upon the edges of the planks or boards of a ship, or vessel, or boat, bottom and sides, and decks as aforesaid, the edges of said planks or boards, being cut according to the form or curvature intended, so that the mechanical force used, will act fairly & equally on the surface of said edges, and on the planks and boards to press the edges closely together, and draw the planks or boards inwardly by the same operation, substantially in the mode herein first above described, in respect to the fastening of the bottoms, and sides and decks of vessels respectively.
